J. Weyer - design for Stove Patented Sept. 25, 1849. -

Ms. 131

James Wager of Troy, New York, Letters Patent No 232, dated September 25, 1848.
The Schedule referred to in these Letters Patent and making part of the same.

To all ~~to whom~~ these presents shall come.
Be it known that I James Wager, of Troy, in the County of Rensselaer, and state of New York, have constructed a new design for Cooking Stoves and that the following is a full clear and exact description of the character which distinguishes it from all other things before known.

My designs consist of certain ornamental plates, and plates of peculiar configuration, to suit the purposes of the stove to which they are adapted. The general figure is oblong, like most

D

Nos. 232

modern stoves for cooking purposes; a moulding surrounds the front and side plates the interior margin of which is carved ornamentally; each of the doors which are three in number on the side shown in the drawing are similarly bordered, with the addition of a bead on the oven door, the centre of each door has an ornament of foliage upon it, and the front upper corner of the oven door is cut off angularly, giving it a pentagonal figure; the front doors are nearly equally divided horizontally, the upper part is ornamented with a foliated ornament, and the lower half is occupied with a lattice damper, as is clearly represented in the perspective view, Fig. 1.

I having thus fully described my improvement, what I claim therein as new, and for which I desire to secure Letters Patent, is the above described ornamental design and configuration of the plates as described and represented.
